ULTRA SHORT WAVE RECEIVER

Bertram Trevor, Riverhead, N. Y., assignor to
Radio Corporation of America, a corporation
of Delaware

Original application May 19, 1936, Serial No.
80,492. Divided and this application March 13,
1940, Serial No. 323,718

13 Claims. (Cl. 250—20)

This invention relates to ultra short radio wave systems, and is a division of my copending application Serial No. 80,492, filed May 19, 1936, now United States Patent No. 2,202,035, granted May 28, 1940.

One of the objects of the present invention is to provide an ultra short wave receiver capable of receiving an extremely wide modulation band, such as might be used in the transmission of television programs. Such a modulation band may be of the order of about three million cycles. A further object is to provide a band pass transformer having balanced primary and secondary circuits of the coaxial line type.

In accordance with the invention, there is employed a novel type of band pass transformer for passing the energy received by the antenna to a balanced detector circuit, to which are fed locally generated high frequency oscillations from a resonant line controlled oscillator. The output of the detector is designed to feed into a cascaded intermediate frequency amplifier which, in turn, may be coupled to a second detector circuit from which the output is amplified and arranged to pass into a suitable utilization circuit.

Various features of the present invention relate to (1) a novel coaxial or concentric line type of band pass transformer, (2) the concentric frequency control line for the local oscillator, and (3) the automatic gain control circuit. Although these features are hereinafter described with particular reference to a receiver circuit, it should be understood that they are not limited thereto, since they are capable of being used in other systems.

Other objects and features, and their advantages will appear more fully hereinafter in connection with the accompanying drawings, Figs. 1, 2, 3 and 4 of which, taken together, illustrate a complete receiving circuit for receiving ultra short waves of the order of 1.7 meters, although it is to be understood that the invention is not limited to this particular wavelength. Fig. 5 is a box diagram indicating how Figs. 1, 2, 3 and 4 should be combined to complete the receiver circuit. Fig. 1a is a cross-sectional view of the coaxial line transformer of Fig. 1 along the lines 1a—1a.

Referring to the drawings in detail, there is shown in Fig. 1 a band pass transformer comprising a plurality of pairs of coaxial or concentric lines 1, 2; 1, 3; 4, 5; and 4, 6. It will be noted that there are two pairs of lines oppositely and symmetrically located with respect to a central metallic plate 7, and that the conductors on one

side of plate 7 are extensions, or on the same straight line with the conductors on the other side of the plate. Since the coaxial lines on each side of the central metallic plate 7 are located next to one another, it is proposed, for purposes of convenience and design, to employ a common outer conductor for both pairs of lines on the same side of the center plate and to accomplish this result the outer conductors are made to have a square form, as shown in Fig. 1a, which is a cross-sectional view of the band pass transformer along the line 1a—1a. The outer conductors 1 and 4 are made of seamless, square, brass or copper tubing and are arranged to be 15 symmetrically positioned with respect to their associated inner conductors. These square tubings are designed to extend beyond the ends of the inner conductors and to be closed at such ends in order to completely shield the entire 20 system. The inner conductors 2, 3; and 5, 6 are joined together at their ends by means of variably balanced condensers C₂, C₃. Each half of the band pass transformer, looked upon from the center toward the ends, is a resonant circuit 25 completely balanced with respect to ground. Both resonant circuits comprising halves 1, 2; 1, 3; and 4, 5; 4, 6 are coupled together at their inner conductors by means of connections 8 and 9 which couple together the inner conductors 30 extending on the same straight line, preferably substantially symmetrically with respect to the center plate 7, as shown. It will thus be seen that we have the equivalent of a transformer comprising two balanced resonant circuits coupled together, each resonant circuit being equivalent, 35 electrically, to a parallel tuned circuit. A damping resistance R, of the correct value, is shown connected across the adjacent ends of the inner conductors of one of the balanced tuned circuits 40 in order to assist in obtaining the desired flat top characteristic of the transformer; that is, so that both balanced halves 4, 5; 4, 6; and 1, 2; 1, 3; may effect a band pass transformer. In certain instances it may be desirable to provide 45 an additional damping resistance across the opposite adjacent ends of the inner conductors of the other tuned resonant circuit, although this is not necessary in the present case. The band pass transformer, just described, is coupled to a suitable input circuit, herein designated the antenna, through a pair of connections 10 which are conductively joined to the inner conductors 2, 3 of one-half of the band pass transformer. This last balanced circuit comprising 1, 2; 1, 3 55 will thus be designated the primary of the trans-

former, and the other balanced tuned circuit to which the output leads 11 are connected, the secondary of the transformer.

The energy received from the antenna over connections 10, and passed on to connections 11 through the band pass transformer, is fed into the grids of a pair of push-pull connected detector tubes 12, 13 to whose cathodes is coupled a line controlled high frequency oscillator 14. It will thus be observed that the received signal waves are applied to the grids of tubes 12, 13 in push-pull (i. e., the signal waves are applied to the grids out of phase with respect to each other), while the local oscillations generated by oscillator 14 are applied to the cathodes of the tubes 12, 13 in push-pull (i. e., in parallel relationship). In the output of the detector tubes 12, 13 there is a transformer L₃L₄ whose primary winding L₃ is balanced with respect to ground but whose secondary winding L₄ is unbalanced with respect to ground and coupled to the intermediate frequency amplifier. A balanced condition of the primary winding L₃ is maintained by the electrostatic shield 15 which symmetrically surrounds the coil. A portion of this shield is positioned between L₃ and L₄. It should be noted that windings L₃ and L₄ comprise a band pass transformer for passing the desired wide modulation band on to the intermediate frequency amplifier.

The local oscillator 14 is stabilized as to frequency by a concentric line comprising an outer conductor 16 and an inner conductor 17, which are conductively coupled together at one of their adjacent ends and capacitively coupled together by capacitor C₁ at their other adjacent ends. The control electrode of oscillator 14 is connected to the outer conductor 16 through the parallel combination of a condenser 18 and a resistor 19.

The anode of oscillator 14, it should be noted, extends through a pipe 20 to the inside of inner conductor 17, near its end and extends, by means of a connection 21, through the entire length of the inner conductor and then to the source of power supply +250 volts. It is preferred that the anode be by-passed to the pipe 20, as shown. The cathode of the oscillator 14 connects with the inner conductor 17 near its middle, while the heater element extends through a pipe 20', also to the inside of the inner conductor 17 near the middle, and then to the heater source of supply. The reasons for this manner of connection may perhaps be more readily explained by comparing the oscillator tube 14 and the line circuit 16, 17 to the well known three point Hartley oscillator circuit as described in United States Patent No. 1,356,763, granted October 26, 1920. Such circuit comprises an inductance whose extreme terminals are coupled to the anode and control electrode and whose cathode is connected to a point intermediate the ends of the inductance. In the present case, the inner conductor 17 acts as the inductance of the Hartley circuit, and it is to the lower end of this inductance 16 that the anode of oscillator 14 extends. The control electrode of oscillator 14, it should be noted, is connected to the outer conductor which is at ground potential. Since this outer conductor 16 is conductively connected to the inner conductor, or inductance 17, at its other end, we thus have a connection from the control electrode to the end of inductance 17 which is opposite the end of the inner conductor connected to the anode. The cathode of oscillator 14, however, extends and is

effectively joined for all purposes, to the middle of the inductance 17, since it enters the inside of inductance 17 near its middle, as previously described and as shown in the drawings. In order to maintain both the cathode and the heater element of oscillator 14 at the same radio frequency potential, so that they fluctuate simultaneously and in the same phase with respect to one another, the heater leads are brought to the middle of the line at substantially the same location to which the cathode element is brought, and extends through the inside of inner conductor 17 to the heater supply. In order to maintain the cathode and heater elements of the detector tubes 12 and 13 at the same radio frequency potential, the connections to these elements are also brought to substantially a single location on the inner conductor for the same reasons hereinabove mentioned with respect to the identical elements of the oscillator tube. It will be noted, however, that the connections to the heater and cathode elements of the detector tubes 12 and 13 are brought to a point on the inner conductor 17 near the conductively connected ends of conductors 16 and 17. This is because the cathodes of detectors 12 and 13 present an appreciable resistance load to the line circuit 16, 17, and the circuit arrangement must be such that this resistance load does not destroy, to a great extent, the oscillator stability of the tube 14 produced by the concentric lines 16, 17. It is desired that the cathodes of the detector tubes be coupled to the inner conductor as near the low potential end of the line 16, 17, in this case the conductively joined end, as possible, but this point of connection cannot be too close to the low potential end for the reason that the detectors require an appreciable exciting voltage to enable them to function as such, and the closer this point of connection is placed toward the low potential end, the less this exciting voltage for the detector will be. It will thus be seen that for efficient operation of the detectors, there will be a point of entrance to the inner conductor from the cathodes of the detector tubes 12 and 13, which will not be too near the low potential end of the resonant line 16, 17 to interfere with the efficiency of the detectors, nor too near the high potential end of the line 16, 17 to interfere with the frequency stability of the control line circuit. The cathodes of the detector tubes, it will be noted, are in circuit with ground through a suitable bias resistor R'. Metal pipes 20, 20' and 20'' serve the useful purpose of preventing undesired capacity effects between the outer conductor 16 and the leads which extend within the pipes, and for this reason the pipes extend slightly beyond the outer surface of the conductor 16.

Coupled to the output of detectors 12, 13 is a cascaded intermediate frequency amplifier system, comprising stages A to F, inclusive, the last stage of which is coupled to the input of a diode second detector tube 22, from which the video frequencies are amplified in video amplifier 23 and then pass on to a suitable utilization circuit through a concentric coupling 24.

For obtaining an automatic gain control there is provided an electron discharge device AGC whose input is coupled to the output of detector tube 22, and whose output is coupled through switch 25, and connection 26, to the control electrodes of several stages of the intermediate frequency amplifier. The control electrode of the AGC tube is substantially at the middle point of a voltage divider comprising the 5 megohm re-

sistance 27 and the 4 megohm resistance 28 to one of whose terminals, namely the lower terminal of the resistance 27, is applied a voltage of -140 volts. Since there is a positive potential of several volts, approximately 5, applied to the upper terminal of resistance 28, it will be seen that there is approximately a negative voltage of about -60 volts applied to the control electrode of tube AGC. Any change in voltage in the output of detector tube 22 will thus cause a slightly smaller change in voltage to be applied to the control electrode of tube AGC, and consequently a very much larger change in voltage appears across resistance 29 in the output of tube AGC, which great change of voltage is available for control of the intermediate frequency amplifier stages. This is due to the fact that tube AGC functions as a direct current amplifier tube, and it should here be noted that the anode, screen and cathode electrodes are connected to a potentiometer in such manner that the voltage progressively increases in positive sense with respect to the control electrode.

Where it is desired to eliminate the use of the automatic gain control circuit, switch 25 is positioned to connect lead 26 with the terminal designated "manual," in which position fixed bias may be applied through lead 26 to the control electrodes of the intermediate frequency amplifiers.

A monitor circuit comprising a tuning indicator having an amplifier detector circuit tube G, serves for enabling the operator to properly adjust the frequency of the local beat oscillator 14 so that the signal carrier will fall on the mid-band frequency of the intermediate frequency amplifier. This monitor circuit is tapped to the input circuit of the line stage F of the intermediate frequency amplifier and includes as one of its elements a sharply tuned resonant circuit 30, the oscillations from which are detected in the triode portion of the tube G and the rectified oscillations indicated in a tuning meter 31. A push button 28 serves to shift slightly the frequency of the resonance curve of the circuit 30 from one side of the mid-band frequency to a point symmetrically positioned on the other side of the mid-band frequency. If the receiver is properly tuned, it will be noted that the connection of the push-button 28 into the circuit will make no difference in the indication of the tuning meter 31.

With the circuit arrangement hereinabove described and shown in the drawings, an extremely stable and satisfactory receiver was designed to function on a single frequency of 177 megacycles, with the local oscillator tuned to a frequency of 156 megacycles, an intermediate frequency mid-band frequency of 21 megacycles, and an intermediate frequency band pass of 3 megacycles. These figures, it is to be distinctly understood, are given by way of example only, and are not to be taken as limiting the invention.

In setting up and making test runs on the receiver, it may be desirable to supply a local signal generator which is arranged to feed locally generated oscillations over a concentric cable to a point near the receiving antenna. In this way the signal generator can be made to radiate energy into the receiving antenna which allows band width and sensitivity checks to be made on the antenna receiver combination. This set-up is provided mainly as a help in properly tuning the receiver.

It will be appreciated that the invention is not limited to the precise arrangement of parts shown

and described, since various modifications may be made in the circuit elements without departing from the spirit and scope of the appended claims.

5 It will also be understood that the term "ground" used in the specification and appended claims is not limited to an actual earthed connection but includes any point of zero or relatively fixed radio frequency potential.

10 What is claimed is:

1. In combination, a pair of electron discharge device detectors, each having an anode, a cathode and a control electrode, said cathodes and anodes being respectively coupled together, an input circuit for applying signal energy to the control electrodes of said detectors in push-pull whereby the applied energy to one control electrode is out of phase with respect to that applied to the other, an oscillation generator stabilized as to frequency by a hollow metallic resonant circuit devoid of concentrated inductance, and means for applying the output of said generator to the cathodes of said detectors in push-push whereby the energy from said generator applied to one cathode is in phase with respect to that applied to the other cathode, said means including a circuit coupled to said resonant circuit and to the cathodes of said detectors.

2. In combination, an electron discharge device oscillation generator having an anode, a filament and a control electrode, a tuned circuit for said generator comprising inner and outer tubular conductors suitably coupled together, a connection from said anode to a source of polarizing potential, said connection extending within and substantially from one end to the other end of said inner conductor, a connection from said control electrode to said outer conductor, and connections from said filament to a source of heating energy, said last connections extending within said inner conductor from a point near the middle of said inner conductor to said last end of said inner conductor.

3. In combination, an electron discharge device oscillation generator having an anode, cathode and control electrode, a tuned circuit for said generator comprising inner and outer tubular conductors, means for capacitively coupling said inner and outer conductors together at one end, means for conductively coupling the other end of said inner and outer conductors together, a connection from said anode to a source of potential, said connection extending within and substantially from one end to the other end of said inner conductor, a source of heating energy for said cathode, and heater leads for said cathode extending within said inner conductor from a point near the middle of said inner conductor to the conductively coupled end of said conductors for connection to said source of heating energy, a connection from said control electrode to said outer conductor, and means for grounding said outer conductor.

4. In combination, an electron discharge device oscillation generator having an anode, a cathode, a heater element, and a control electrode, a tuned circuit for said generator comprising inner and outer tubular conductors capacitively coupled together at one end and conductively coupled together at their other end, a connection from said anode to a source of potential, said connection extending within and substantially from one end to the other end of said inner conductor, a connection from said control electrode to said outer conductor, a connection from

said cathode to a point on said inner conductor near its middle, and connections from said heater element to a source of heating energy, said last connections extending within said inner conductor from a location adjacent said point to said last end of said inner conductor, and means for grounding said outer conductor.

5. Apparatus in accordance with claim 4, characterized in this that said anode connection enters said inner conductor at a point near the capacitive coupled ends of said tubular conductors.

6. Apparatus in accordance with claim 2, including tubular shields located between said inner and outer conductors and extending slightly beyond said outer conductor and insulated therefrom for accommodating and shielding the connections extending from the electrodes of said electron discharge device to the interior of said inner conductor.

7. In combination, an electron discharge device oscillation generator having an anode, cathode and control electrode, a tuned circuit for said generator comprising inner and outer tubular conductors suitably coupled together, means for applying a positive potential to said anode including a connection from said anode extending within and substantially from one end to the other end of said inner conductor, a connection from said control electrode to said outer conductor, and heater leads for said cathode extending within said inner conductor from a point near the middle of said inner conductor to said last end of said inner conductor, an electron discharge device detector having electrodes, and a connection from one of the electrodes of said detector extending within said inner conductor from a point near the low potential end of said inner conductor to said last end.

8. In combination, an electron discharge device oscillation generator having an anode, a cathode, a heater element, and a control electrode, a tuned circuit for said generator comprising inner and outer coaxially arranged tubular conductors capacitively coupled together at one end and conductively coupled together at their other end, means for applying a suitable polarizing potential to said anode including a connection from said anode extending within and substantially from the high potential end to the low potential end of said inner conductor, a connection from said control electrode to said outer conductor, a connection from said cathode to a point on said inner conductor near its middle, and connections from heater leads for said heater element extending within said inner conductor from a location adjacent said last point to said low potential end of said inner conductor, a connection from ground to said outer conductor, an electron discharge device detector having a cathode and a heater element, and connections from said cathode and heater element of said de-

tector extending within said inner conductor from a point substantially near its low potential end to said last end.

9. Apparatus in accordance with claim 8, including metallic tubular shields located between said inner and outer conductors and extending slightly beyond said outer conductor and insulated from said outer conductor for accommodating and shielding the connections extending from the electrodes of said electron discharge devices to the interior of said inner conductor.

10. An oscillation generator comprising an electron discharge device having a cathode and a pair of cold electrodes, a tuned oscillatory circuit comprising means having a substantially completely enclosed electromagnetic field therein and being devoid of concentrated inductance, a connection from said cathode to an effectively intermediate portion of said tuned circuit, and means for inductively coupling said pair of cold electrodes to portions of said tuned oscillatory circuit which have opposite polarities relative to said cathode.

11. An oscillation generator comprising a tuned oscillatory circuit in the form of a pair of coaxial conductors directly connected together from a direct current standpoint at one end and capacitively coupled together at the other end, a vacuum tube having a cathode, a grid and an anode, connections from said grid and anode to substantially opposite ends of said tuned circuit, and a connection from said cathode to an intermediate portion of said tuned circuit.

12. In combination, an electron discharge device oscillation generator having an anode, a filament and a control electrode, a tuned circuit for said generator comprising inner and outer tubular conductors suitably coupled together, said electron discharge device being located externally of the tubular conductors of said tuned circuit, a connection from said anode to a source of polarizing potential, said connection extending within and substantially from one end to the other end of said inner conductor, a connection from said control electrode to said outer conductor, and connections from said filament to a source of heating energy, said last connections extending within said inner conductor from a point near the middle of said inner conductor to said last end of said inner conductor.

13. An oscillation generator comprising a tuned oscillatory circuit in the form of a pair of coaxial conductors suitably coupled together and short circuited for the operating frequency substantially at one end, a vacuum tube having a cathode, a grid and an anode, connections from said grid and anode to substantially opposite ends of said tuned circuit, and a connection from said cathode to an intermediate portion of said tuned circuit.

BERTRAM TREVOR.
